UNITED STATES PATENT OFFICE.

OVERTON WINSTON, OF MINNEAPOLIS, MINNESOTA.

HEADLIGHT.

1,273,970.

Specification of Letters Patent. Patented July 30, 1918.

Application filed October 5, 1916. Serial No. 123,848.

To all whom it may concern:

Be it known that I, OVERTON WINSTON, a citizen of the United States, residing at Minneapolis, in the county of Hennepin and 5 State of Minnesota, have invented certain new and useful Improvements in Headlights; and I do hereby declare the following to be a full, clear, and exact description of the invention, such as will enable others 10 skilled in the art to which it appertains to make and use the same.

Particularly, my invention relates to headlights provided with shifting light sources within concave reflectors, and the invention 15 provides, in combination therewith, a frosting or light dimming obstructing surface of novel relative arrangement, all as will hereinafter more fully appear.

The invention is illustrated in the accompanying drawings wherein like characters indicate like parts throughout the several views. Referring to the drawings:

Figure 1 shows the reflector in vertical section and a two-filament light bulb in 25 side elevation; and

Fig. 2 is a front elevation of the headlight, parts of the reflector being broken away.

The reflector is indicated by the numeral 30 1 and the light bulb by the numeral 2. This light bulb has two filaments, the hot spots of which are indicated, one at *a* and the other at *b*. The hot spot of filament *a* is at the axis of the reflector and the hot spot of 35 the filament *b* is vertically offset and materially above the axis of the reflector.

In practice, the two filament light bulb employed may be and preferably is combined with electrical connections and switches, 40 such, for example, as illustrated in my pending application, S. N. 86,852, filed March 27, 1916, and entitled "Headlights."

In Fig. 1, line *c* radiates from *b* to the upper edge of the reflector; line *d* is a horizontal line or line parallel to the axis of the reflector and which intersects point *b*, and line *e* is a line that radiates from *b* at an upward inclination to line *d* and about midway between lines *c* and *d*.

50 The globe of the light bulb 2 is provided with a frosting or light dimming surface 3 on its upper front portion. When the bulb globe is spherical, this frosting 3 will be truly circular, but in any case it has a margin that lies in a single plane so that it may,

for example, be produced by dipping in a liquid which has a chemical action on glass. The lower edge of the frosting 3 extends down to a horizontal line *d* while the upper edge thereof extends to the line *e*. 60

For long beam projection, such as required for country road driving, the light source will be at filament *a*, while for city driving, where objectionable blinding must be avoided, the light source will be at filament *b*. With this arrangement, when the light source is at *b*, all of the direct rays which are in a vertical plane and above the horizontal line *d* and below oblique line *e*, will be dimmed by frosting 3. The direct 70 rays from *b* which are in a vertical plane between lines *e* and *c* are not dimmed, but have such upward angular projection that they will not strike the eyes of a person in a passing machine until the passing machine 75 is so close that the rays will be from one side and not directly in the line of vision of a person in a passing machine, and hence, will not produce serious blinding effect.

The frosting above described is about the 80 smallest size capable of use for the prevention of serious blinding effects and has the further advantage that it may be produced by dipping. The said frosting, because of its smallness and relative location, will produce a minimum shadow effect in the long 85 projected beam from source *a*.

What I claim is:

In a headlight, the combination with a reflector, of a two-filament light bulb there- 90 in, said bulb having two filaments, one at the axis and the other above the axis of said reflector, and the globe of said bulb having an approximately circular frosting or light dimming surface on its upper front portion, 95 the upper edge of said frosting being terminated materially below a line that radiates from said upper filament and intersects the upper portion of the rim of said reflector, and the lower portion of said frosting being 100 extended down to a line that radiates from said upper filament horizontally or parallel to the axis of said reflector.

In testimony whereof I affix my signature in presence of two witnesses.

OVERTON WINSTON.
